SHOPPING REMINDER

Eugene Farkas, New York, and Amram Haddad,
Bronx, N. Y.

Application February 5, 1954, Serial No. 28,854

Term of patent 7 years

(Cl. D52—1)

Fig. 1.

Fig. 2.

To all whom it may concern:

Be it known that I, Eugene Farkas, a citizen of the United States of America, residing at New York, county of New York, N. Y., and I, Amram Haddad, a citizen of the United States of America, residing at Bronx, county of Bronx, N. Y., have invented a new, original, and ornamental Design for a Shopping Reminder, of which the following is a specification, reference being had to the accompanying drawing, forming part thereof.

Fig. 1 is a top view of a shopping reminder, showing our new design.

Fig. 2 is a side elevation of the same.

We claim:

The ornamental design for a shopping reminder, as shown.
